Reissued Mar. 6, 1923.

Re. 15,557

UNITED STATES PATENT OFFICE.

AUGUST ALBERT, OF MUNICH, GERMANY.

METHOD OF PRODUCING NEW AROMATIC COMPOUNDS CONTAINING CARBONYL GROUPS WITH TRIVALENT ARSENIC.

No Drawing. Original No. 1,425,931, dated August 15, 1922, Serial No. 548,794, filed March 25, 1922.
Application for reissue filed January 5, 1923. Serial No. 610,900.

To all whom it may concern:

Be it known that I, AUGUST ALBERT, a citizen of the Republic of Germany, and residing at Munich, Germany, Elisabethstrasse 46, have invented a new and useful Method of Producing New Aromatic Compounds Containing Carbonyl groups with Trivalent Arsenic, of which the following is a specification.

10 It is well known that the carbonyl group in aldehydes and ketones is very reactive and therefore aldehydes and ketones react very easily with reagents of the most varied nature. For example, it is generally known 15 that these bodies can be easily reduced by a great variety of reducing agents. It is further known that the carbonyl group forms with bisulphites and hydrosulphites addition products which may be regarded as esters. 20 Another example of the reactivity of the carbonyl group is given by Fossek (Wiener Monatschafte, vol. 5, p. 625, and vol. 7, p. 20) who shows that aldehydes, ketones, acid amids, etc., form phosphonic acids.

25 I have now discovered that it is possible to subject arsenic compounds such as those of the aromatic series which contain one or more carbonyl groups in non-cyclic linkage with an arsonic acid nucleus, to reduction 30 in such manner that the arsenic group only is reduced. By the term carbonyl group in non-cyclic linkage, I mean, a carbonyl group contained in a side chain. In this manner, for example arsonic acids of the type 35 R—As=O₃H₂, where R is an aromatic group containing one or more carbonyl groups, are reduced to the corresponding oxides

40 and these oxides can be further reduced to the arsено compounds R—As=As—R, in non-cyclic linkage, without the carbonyl groups having been attacked.

For conducting this selective reduction of 45 pentavalent arsenic in organic compounds, sodium hydrosulphite, phosphorous trichloride, phosphorous acid and halogen iodide, sodium bisulfite and the like are especially adapted.

50 The new substance containing trivalent arsenic produced in the aforesaid manner possesses valuable therapeutic properties and from it can be prepared derivatives which are effective in the control of the *Bacillus*

trypanomiasis and the *Bacillus spirochasta* 55 *pallida*. To illustrate different methods of practising my invention the following examples are given.

1. 5 grams benzaldehyde-arsonic acid

60

65

are dissolved in 44 ccm. normal sodium hydrate (—2 molecules) and thereto are added 80 ccm. of water. To this solution is added a solution of 50 gms. sodium hydrosulphite and 10 gms. chloride of magnesia in 200 ccm. of water and this mixture is stirred 1½ to 2 hours at a temperature of about 60° C. The desired arsено benzaldehyde separates out. It is then filtered by suction and washed and dried in vacuo. The resulting product 70 has a dark color, it decomposes at about 260° C.

2. 6.6 gms. 1-oxy-6-nitro-2-butyro-4-arsonic acid

80

85

are dissolved in 100 ccm. normal NaOH, which solution is diluted with 70 ccm. water. This solution is added with stirring to a solution of 13 gms. chloride of magnesium and 76 grams of sodium hydrosulfite in 330 ccm. water. It is stirred at a temperature of about 60° for 1 to 1½ hours. The precipitate is filtered with suction, washed and dried in vacuo. The arsено benzol so obtained gradually darkens at about 100° C. without melting.

3. 1 gm. p-acetonphenonarsonic acid is

100

poured into a solution of 5 ccm. sodium bisulphite. By heating with a free flame the substance is for a moment dissolved but then at once the separation of the arsenic

oxide begins. The reaction is completed by heating for half an hour on the water bath. It is then filtered with suction, washed and dried on a piece of porous earthenware. 5 The arsenic oxide forms a sodium salt difficult to dissolve in normal NaOH, but it may be dissolved by addition of water. By means of a solution of ammonium chloride the arsenic oxide can be separated again out 10 of this solution as a white voluminous precipitate. The oxide decomposes at a temperature of about 260-265° to a dark brown mass.

14. 1.2 gms. 1-oxy-6-nitro-2-acetophenon

15

20

arsonic acid is dissolved in 24 ccm. water and 8.8 ccm. normal sodium hydrate and filtered. 0.4 gm. potassium iodide and 16 ccm. sulphuric acid (1.5) are added to this solution 25 and then sulphur dioxide is passed into the solution for about 1 hour, meanwhile cooling the solution with water. The mixture is then allowed to remain in the vessel for 24 hours, the arsenic oxide so produced is then 30 filtered with suction and dried on a piece of porous earthenware. The arsenic oxide is redissolved and separated by a solution of ammonium chloride. At a temperature of about 230° to 235° the arsenic oxide decomposes to a dark brown mass.

35

Claims:

1. Process of preparing an aromatic compound containing trivalent arsenic and a carbonyl group which consists in treating with a reducing agent an aromatic compound which contains a carbonyl group in non-cyclic linkage and an arsonic acid group attached to the benzol ring. 40

2. Process of preparing an aromatic compound containing trivalent arsenic and a carbonyl group which consists in treating with sodium hydrosulphite an aromatic compound which contains a carbonyl group in non-cyclic linkage and an arsonic acid group attached to the benzol ring. 45

3. As a new compound, a substance containing the group R—As—, in which R comprises an aromatic group to which is attached a carbonyl group.

4. As a new compound, 1-4 arsono benzaldehyde of the general structure 50

60

In testimony whereof I have signed my name to this specification in the presence of 65 two subscribing witnesses.

AUGUST ALBERT.

Witnesses:

ALEXANDER DE SOTO,
ALEXER V. PHILIPPOFF.
